KNOCKDOWN BOX

Eldred Tait Hunter, Washington, D. C., assignor
to Material Progress Corporation, Washington,
D. C., a corporation of Delaware

Application August 13, 1947, Serial No. 768,356

3 Claims. (Cl. 217—7)

1

My invention relates to a knock-down box or crate, the several parts of which are held together without the use of the usual type of fastener and may be readily set up or taken apart for trans-shipment in a knock-down state. It consists in certain details of construction and combination of parts as are shown in the accompanying drawings and described in this specification.

It is an object of this invention to construct a box that may not be opened during transit for the removal of a portion or all of the contents thereof and reassembled so that the pilfering is not evident until the final destination is reached. This is accomplished by having interlocking joints. The side walls made of ply-wood are fastened to the cleats with clinched staples which do not permit removal and replacement in such a manner as to hide their removal.

It is a further object of this invention to assemble the box so that the only removable fastening is at one end of the top section which may consist of a bolt or wire which would act as a seal so as to show any tampering with this fastening.

In the drawings:

Figure 1 is a perspective assembled view of the box.

Fig. 2 is a cross section taken on the line 2—2 of Fig. 1.

Fig. 3 is a cross section taken on the line 3—3 of Fig. 1.

Fig. 4 is a cross section taken on the line 4—4 of Fig. 1.

Fig. 5 is an expanded view of the box showing the method of assembling the various parts.

Fig. 6 is a perspective view of a modification of this invention with the top removed showing the interior construction of the box.

Similar reference characters indicate similar parts throughout the several views.

The box as shown in the expanded view, Fig. 5, consists of two end panels 35 and 36, two side panels 30 and 31, a bottom panel 32 and a top panel 33 and a center panel 34.

In the construction of this box I show cleats 10 at the top and cleats 12, 12 at the bottom of one end panel 35 having the hole 19 for the admission of the seal or bolt, and the cleats 11, 11 and 12, 12 on the other end panel 36. The cleats on the bottom panel 32 are 13, 13 on the upper surface of this panel which overlaps and interlocks with the cleats 12, 12 on the bottom of both of the end panels and the four exterior cleats 14 which together with the cleats 12, 12 which are

overlapped by the ends of cleats 13, 13 support the weight of the box when the box is assembled. The side panels 30 and 31 are not identical but are mirror-image sections and have the 5 interior and exterior cleats 15, 15', the interior cleat 15 being longer than the exterior cleat 15' which allows for the cleat 13 of the bottom panel and the interlocking cleat 16 of the top panel 33. The top panel 33 has cleats 21, 22 and 23, 23 on its upper surface and cleats 16, 16 on its lower surface extending beyond one end of the panel to interlock with the cleats 11, 11 of the end panel 36.

In assembling this box the bottom panel is 10 laid in place, the two end panels are so placed that the long cleat 13 overlaps the bottom cleats 12, 12 of the end panels. The side panels are 15 brought into position so that the interior long cleat 15 comes on the outside of the end panels 20 35, 36, and inside of the bottom cleat 13 thereby giving an interlocking joint which cannot be disassembled without the removal of the side panel. Each is held in place at the top by the side cleat 25 16 of the top panel which is longer than the panel and extends over the top of the short cleat 15' and under the long cleats 11, 11 of the end panel 36, the cleats 15' being on the outside of the side panel and prevents the removal of the panel and the hole 18 at the end of the top panel is aligned 30 with the hole 19 in the end panel 35, both of these holes going through the panel itself and the cleat attached thereto and permits the fastening of the end panel and the top panel by means of a seal or bolt so as to maintain the hole 35 in alignment and prevents the removal of any part of this box without actually breaking one of the panels or cleats. All of the panels are 40 permanently fastened to their cleats by means of clinched staples which prevent the removal of the fastenings and their replacement without being readily discernable by visual inspection.

This invention also includes the insertion of an interior panel 34 which is held in place by being mortised into the side panels 30 and 31 45 and the exterior cleats 24 and 25 placed on the exterior surfaces thereof. This panel is also mortised into the cleat 26 placed on the exterior surface of the bottom panel 32 and is brought into position immediately below the cleat 27 on 50 the upper surface of the top panel. This gives additional rigidity to the box and will allow an interior partition which will divide the box into two parts. This partition 34 may be used as a base for fastening the articles that are packed therein. Examples of this type are small motors

which may be bolted to the panel 34. A series of panels such as are shown in Fig. 6, may be assembled as described above to give a box containing a plurality of compartments which may be used to ship small articles, in particular bottled goods. It is readily seen that where the center partition is shown as being mortised into the adjoining panels and the cleats exterior thereto, with the exception of the top panel, it could of course have these cleats mortised and extend into the cleats exterior to the top panel also. Where mortised and tenon joints are shown as a means of holding the center panel 34 in place interior cleats on each side of this panel could be used to give a tongue and groove method of holding this panel in place.

My invention is illustrated by the above description but it should not be limited thereto as certain variations are possible and may be desirable, for instance, two holes could be placed in the cleat 19 of the end panel and in the cleat 21 of the top panel. These holes would permit double sealing or a stronger bolt fastening or both. The invention is described as having clinched stapled fastenings but any type of permanent non-removable fastenings may be used.

In this manner a new demountable box is constructed which is characterized by the fact that the sides of the box are fitted with reinforcing cleats, which cleats lie wholly without the assembled box giving a finished box having perfect rectangular cross section at all points. All of the cleats are permanently fastened and the only removable fastenings that are used are the seal or bolts at the end of the top section.

The advantages of this box are self-evident. It allows trans-shipment of goods in a light, strong container where tampering with the container may be detected by a casual inspection. The ply-wood panels are held rigidly by cleats placed at the ends thereof so that they may not be sprung out of position and the overlapping cleats of the adjacent panels hold the box in an assembled condition. There are no cleats on the interior parts of the box so a perfect packing container is obtained without any interior projections. The cleats are so arranged on the outside as to give a perfect crate so far as the outer surface is concerned so that it may be stacked in the hold of a ship or palletized with the greatest advantage. This would not be true of a box or crate having a flat side with protuberances at each end only thereof which could interlock and cause difficulty in stacking.

This invention contemplates the use of a solid sheet or slats in making the panels referred to above. In the example cited in this application ply-wood has been used but the invention should not be limited to ply-wood as it comes within the scope of this invention to use any suitable substance.

What is claimed is:

1. A knock-down box having a solid bottom panel having cleats on its upper surface and having cleats on its lower surface, said upper cleats being longer than the panel, one solid end panel having upper and lower cleats on the inner and outer surface which cleats are longer than the panel, the lower cleats interlocking with the long cleats of the bottom panel, a second solid end panel having cleats on the bottom inner and outer surface which cleats interlock with the long cleats of the bottom panel and having a single cleat on the top outer surface, two solid side panels having inner and outer cleats at both ends, which cleats interlock with the long cleats on the bottom panel and overlap the edges of the end panels, a solid top panel having upper and lower cleats, said lower cleats extending beyond one end of the panel so that the cleats interlock under the upper cleats of the end panel and come flush with the interior surface of the other end panel and overlap the upper edges of the side panels, and fastening means at the flush end of the top panel.
2. A box as claimed in claim 1, having a fastening and sealing means at one point at one end thereof.
3. A box as claimed in claim 1 having interior divisional panels removably fastened through the adjoining surfaces.

ELDRED TAIT HUNTER.
